PULLING-LAMP-FIXTURE

Karl Reeber, Oenekinger Weg 9, Luedenscheid,
Westphalia, Germany

Filed June 16, 1959, Ser. No. 820,710

Claims priority, application Germany Apr. 25, 1959
4 Claims. (Cl. 240—71)

The present invention relates to a pulling-lamp-fixture with a spring pull operating in one direction, which spring pull is disposed preferably in a ceiling canopy. The lamp cord carries at one end the lamp socket and the fixture, respectively, while its other end may be wound on a winding drum rotatably mounted in a frame and adjustably spring biased. The winding drum has furthermore means for transferring current between the network and the lamp cord.

It is one object of the present invention to provide a pulling-lamp fixture including a spring-pull, which will project only a relatively short distance beneath the ceiling upon which it is mounted.

It is another object of the present invention to provide a pulling-lamp-fixture wherein the bushing, which supports the spring-pull frame, projects through the bottom of the ceiling canopy in downward direction and is connected with a covering or centering cap which has an inner threaded collar and covers the bushing together with the entire bottom of the canopy and which has preferably a different color than that of the canopy.

It is yet another object of the present invention to provide a pulling-lamp-fixture wherein the conically formed covering or centering cap is equipped with a threaded collar which projects into the bottom of the ceiling canopy and which receives the bushing over the entire length of the latter and is disposed flush with the inner side of the bottom of the canopy. The outer edge of the cap engages the shoulder of a ring projecting axially in downward direction, which shoulder is formed by the bottom of the canopy.

With the structure designed in accordance with the present invention it is possible that the ceiling canopy which receives the spring-pull appears optically much lower than the known structures, since the construction height of the actual canopy is in this manner reduced for the length of the bushing provided on the frame. The covering cap which receives now the bushing in a covering manner is no more recognized as to the construction height, particularly since advantageously it is in a color different from that of the canopy. This conically shaped covering cap amounts to a reliable solution on the one hand as to the mounting or securing, and on the other hand of an aesthetic and well constructed formation of the bottom of the canopy, and finally makes the total ceiling canopy appear shorter for an appreciable amount, so that this embodiment lives up to all desired requirements of a ceiling spring-pull covered by a ceiling canopy. Threaded nipples or the like do not appear at all in this structure. Furthermore, the axially projecting shoulders of the bottom of the canopy contribute to the safe centering of the cap, while on the other hand the shoulder of the cap which receives the frame bushing secures a safe centering of the spring-pull.

This new embodiment of the present invention brings about also a mounting of the spring-pull frame in an advantageous manner. The mounting of the fixture is achieved in such a manner that by means of the proposed eye or hook, a spring-pull frame needs to be hooked merely to the ceiling hook, whereby the cumbersome mounting by means of a U-shaped, bent securing member, as applied in a known structure, is eliminated.

With these and other objects in view, which will be-

2

come apparent in the following detailed description, the present invention will be clearly understood in connection with the accompanying drawings, in which:

FIGURE 1 is a pulling-lamp-fixture with a spring pull disposed in the ceiling canopy;

FIG. 2 is a longitudinal section through the ceiling canopy with a spring-pull, partly in section, whereby the bottom of the canopy and the frame bushing are covered by a covering cap; and

FIG. 3 is an elevation of the pulling-lamp-fixture, another embodiment of the covering cap being shown in section.

Referring now to the drawings, and in particular to FIGS. 1 and 2, a spring-pull 10 is disposed in a ceiling canopy 11, whereby the spring-pull 10 is mounted on a ceiling hook 12. The feeding of electric current from a current source including feeding wires 19 onto the winding cord 22 takes place by means of the axles 15 and 16 which carry the respective halves of the winding rollers 13 and 14 and from here over the contact springs 17 and 18, secured to the spring-pull 10 by means of contact screws 22², onto the terminal ends 22' of the winding cord 22, on the end of which the lamp socket 42 together with the lamp shade 43 is mounted. The respective halves of the winding rollers 13 and 14 have substantially half-circular complementary recesses 13' and 14' through which the winding cord 22 is fed from the interior of the winding rollers 13 and 14 toward their outer faces on which the winding cord 22 is wound.

The spring-pull frame 36, which supports the axles 15 and 16 in an axially aligned position, is held together by means of a frame bushing 40 which, in accordance with the embodiment of the present invention shown in FIG. 3, projects through the bottom 44 of the canopy 11, and is carried by an inner threaded cylindrical member 45 of a covering cap 46. This member 45 projects on the one hand through the bottom 44 of the canopy 11 and terminates at its inner side flush with the latter. Furthermore, the cap 46 has a substantially conical shape and is centrally supported or guided with its edge 47 on an axially projecting shoulder 48 of the bottom 44 of the canopy 11.

In the embodiment shown in FIG. 2 of the drawing, the bottom 44 of the canopy 11 has an axially projecting annular member 49 through which the frame bushing 40 extends, whereby a comparatively short cylindrical member 45' of the covering cap 46 may be screwed on, or merely fit on the free remaining part of the frame bushing 40, and thereby a safe mounting is secured.

The mounting of the spring-pull frame 36 is arranged in such a manner that eyes 30 stamped out from the upper cross member 29 of the frame receives the ends of a fixing stirrup 50 which is interlocked with the eyes 30. This stirrup 50 is in this manner connected with the upper cross-member 29 of the frame and it is not required to mount the stirrup 50 during the mounting of the spring-pull. The spring-pull is supported from the ceiling hook 12 by means of said stirrup 50.

As already set forth, the shown and described embodiments of the present invention are merely examples for supplying a structure of the present invention and are not limited thereto, rather other embodiments and applications are possible within the scope of the present invention. This relates in particular to the constructive formation of the covering or centering cap, as well as its collar, the scope of the present invention being determined by the objects and the claims.

I claim:

1. A pulling-lamp-fixture, comprising in combination a spring-pull effective in one direction and including a winding drum, a spring-pull frame, two axle members sup-

ported by said spring-pull frame and disposed at the same axis and rotatably supporting said winding drum in said frame, a lamp cord supporting a lamp socket at one end and wound on said winding drum, said winding drum comprising two halves and each of said axle members being inserted through the end face of the corresponding half of said winding drum, and disposed in said drum, a radially disposed contact spring secured to each half of said winding drum and engaging, adjacent one of its ends, the inner end of the corresponding of said axle members, the other end of said axle members being connected with current feeding wires, a contact screw on each half of said winding drum for securing said contact springs and the other end of said lamp cord, with a ceiling canopy receiving said spring pull and having a bottom portion, a bushing connected to the lower end of said frame, and said bushing supported by said spring-pull frame and projecting downwardly from said bottom portion of said canopy, and a covering and centering cap receiving said bushing by means of an inner engaging cylindrical member, said cap covering said bottom portion of said canopy and having a color different than that of said canopy.

2. The pulling lamp fixture, as set forth in claim 1, wherein said covering and centering cap is of conical shape in downward direction and said cylindrical member engaging said bushing in axial direction over its entire length, said covering and centering cap terminating flush

20

5 with the inner face of said bottom portion of said canopy and said bottom portion having at its periphery a downwardly projecting ring shoulder and the outer edge of said cap engaging said shoulder of the bottom of said canopy, thereby centering said cap on the bottom portion of said canopy.

3. The pulling-lamp-fixture, as set forth in claim 1, wherein the bottom of said canopy has a downwardly projecting cylindrical member for a part of the axial length 10 of the bushing and said cap has a complementary axially upwardly projecting cylindrical member, both said axial members engaging said bushing in axial direction.

4. The pulling-lamp-fixture, as set forth in claim 1, wherein said frame has a crosswise disposed upper member and at least two eye portions being stamped out from said cross-member and a securing stirrup having end portions received in said eyes of said cross-member.
